CLAIM

We claim the ornamental design for a top of wall ventilation screed device, as shown and described.

DESCRIPTION

FIG. 1 is a perspective view of a top of wall ventilation screed device showing our new design;

FIG. 2 is a front side view of the top of wall ventilation screed device;

FIG. 3 is a back side view of the top of wall ventilation screed device;

FIG. 4 is an end view of the top of wall ventilation screed device;

FIG. 5 is another end view of the top of wall ventilation screed device;

FIG. 6 is a side view of the top of wall ventilation screed device;

FIG. 7 is another side view of the top of wall ventilation screed device; and,

FIG. 8 is another perspective view of the top of wall ventilation screed device.

The broken lines in FIGS. 1-4 and 7-8 represent portions of the top of wall ventilation screed device and form no part of the claimed design.
